[57] CLAIM

The ornamental design for a ceiling mounted electronic air cleaner enclosure, as shown and described.

DESCRIPTION

FIG. 1 is a bottom plan view of a ceiling mounted electronic air cleaner enclosure, showing our new design, this view being common to two embodiments of said enclosure;

FIG. 2 is a perspective view as seen from the bottom, a first side and a first end, of a first embodiment of our ceiling mounted electronic air cleaner enclosure design; FIG. 3 is a side elevation view, on a reduced scale as seen from the side shown in FIG. 2, the opposite side being a mirror image thereof;

FIG. 4 is an end elevation view, on a reduced scale as seen from the end shown in FIG. 2, the opposite end being a mirror image thereof;

FIG. 5 is a perspective view, as seen from the bottom, a first side and a first end, of a second embodiment of our ceiling mounted electronic air cleaner enclosure design; FIG. 6 is a side elevation view, on a reduced scale as seen from the side shown in FIG. 5, the opposite side being a mirror image thereof; and,

FIG. 7 is an end elevation view on a reduced scale of the end shown in FIG. 5, the opposite end being a mirror image thereof.

The top of the design is substantially flat and unornamented.
